US00D890870S

(12) **United States Design Patent** (10) Patent No.: **US D890,870 S**
Jones et al. (45) Date of Patent: **** Jul. 21, 2020**

(54) **FAN BLADE**

- (71) Applicant: **Coulter Ventures, LLC.**, Columbus, OH (US)
- (72) Inventors: **Dylan Jones**, Santa Barbara, CA (US); **Matt Dubberley**, Santa Barbara, CA (US); **Patrick Burgess**, Cullowhee, NC (US)
- (73) Assignee: **Coulter Ventures, LLC.**, Columbus, OH (US)
- (**) Term: **15 Years**
- (21) Appl. No.: **29/723,654**
- (22) Filed: **Feb. 10, 2020**

Related U.S. Application Data

- (63) Continuation of application No. 29/701,244, filed on Aug. 9, 2019, now Pat. No. Des. 878,500, which is a continuation of application No. 29/658,643, filed on Aug. 1, 2018, now Pat. No. Des. 861,809.

CLAIM

The ornamental design for a fan blade, as shown and described.

DESCRIPTION

FIG. 1 is a top, front, right perspective view of a fan blade showing my new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines depicting the remainder of the fan blade of FIGS. 1-7 show features that form no part of the claimed design.
